UNITED STATES PATENT OFFICE.

JULIUS A. MEYER, OF ST. LOUIS, MISSOURI.

FOOT-OPERATED BASS-DRUM AND CYMBAL BEATER.

1,016,510.

Specification of Letters Patent.

Patented Feb. 6, 1912.

Application filed April 10, 1911. Serial No. 620,167.

To all whom it may concern:

Be it known that I, JULIUS A. MEYER, a citizen of the United States, and resident of St. Louis, Missouri, have invented certain new and useful Improvements in Foot-Operated Bass-Drum and Cymbal Beaters, of which the following is a specification containing a full, clear, and exact description, reference being had to the accompanying drawings, forming a part hereof.

My invention relates to an improved foot-operated bass-drum and cymbal beater, and consists in the novel construction and combination of elements hereinafter described and pointed out in the appended claims.

The object of my invention is to provide an improved bass-drum and cymbal beater, which shall be capable of being "knocked-down" or folded and carried in the operator's pocket, and yet possess sufficient weight to be amply durable and efficient.

In the drawings: Figure 1 is a side-elevation of my improved device, applied to a bass-drum, unnecessary parts of the latter being broken away. Fig. 2 is a rear-elevation of the device. Fig. 3 is a detail sectional plan-view of the cymbal striker, illustrating its reversible clamp whereby it is reversibly and adjustably carried by the drum-beater rod. Fig. 4 is a front-elevation of my invention, applied to a bass-drum and cymbal, portions of the latter and the drum being broken away. Fig. 5 is a detail plan-view of my improved hoop-clamp applied to a cymbal-holder. Fig. 6 is a sectional detail view of the cymbal-holder loop-clamp.

The numeral 1 indicates the treadle-base preferably made in the form of a light casting, to the outer end of which the heel of the treadle 2 is pivotally connected at 3. Fixed upon the upper surface of the base hoop-clamp 4 is an integral one-piece beater-post 5 having a vertical slot 6 in its lower portion, and provided with a bifurcated upper end 7. Rotatively-mounted in the bifurcation of the upper end of said post, and held therein by the pivot-pin 8, is the beater-rod arm 9. Detachably-located in a seat 10 in the outer free portion of said beater-rod arm 9 is the lower end of the beater-rod 11, the same being secured by a common thumb-screw 12. On the underside of said arm 9, at or near the outer free end of same, is a perforated lug 13. Projecting from the toe 55 of the treadle 2 is a treadle-arm 14, which projects centrally of said treadle through

and beyond the vertical slot 6 of the said beater-post 5; and the free end of said arm 14 is provided with a notch 15 in its lower edge at a point in rear of said post. A connecting-rod, or wire, 16 has common hooks or loops at its ends, and its upper end is connected to said perforated-lug 13 of said arm 9, while the lower end of said connecting-rod is detachably-mounted in said notch 15 of said treadle-arm 14; thereby connecting said treadle-arm to said beater-arm 9. Two bow-springs 17 and 18 have their lower arms fixed in apertures 19 formed in a rearwardly-projecting lug 20 near the upper end 70 of said post 5, while the upper arms of said springs engage the underside of said beater-arm 9, to normally hold the parts in the position in which they are shown in full lines in Figs. 1 and 4. The base hoop-clamp 4 is 75 detachably connected to the treadle-base 1, by means of common thumb-screws 21 which engage the overlapping inner edge of said base and the underlying portion of said hoop-clamp 4. The rear, or inner, edge of 80 said base hoop-clamp is constructed in the following manner: Integral clamping-arms 22 project upon the upper surface of said part 4, and extend inwardly or rearwardly far enough to form a hoop-space between 85 them and the underlying surface of the said hoop-clamp, so that in use the hoop 23 of the drum will be located in said hoop-space. Common thumb-screws 24 are threaded through said arms 22, so that their inner 90 free ends will bear upon a movable clamping-jaw 25 and force the same into contact with the said drum hoop. Said movable clamping-jaw 25 is preferably made of a strip of spring-metal, so that when pressed 95 into contact with the drum-hoop by the action of said thumb-screws 24, the said jaw will yield and conform itself to the curved surface of said hoop, and thereby greatly enlarge the contact-surface and form a more 100 efficient clamping-jaw. (See Figs. 2 and 6). The ends of the said conformable-jaw 25 are bent into L-shape, so that they will engage the outer sides and upper surface of the clamping-arms 22 in a rather loose manner, 105 to permit the jaw to bend in conforming itself to the curve of said drum-hoop, and yet loosely secure itself to the said arms for purposes of support when the jaw is not in use. The beater-rod 11 is provided with the ball 110 26 at its free end, and intermediate of the said ball and the inner end of said rod the

cymbal-striker bracket 27 is adjustably mounted. The said bracket 27 is provided with a transverse-slot 28 in which the cymbal-striker 29 is loosely mounted, and a 5 thumb-screw 30 passes through an aperture in the slotted walls of said bracket, and is through an aperture in said striker, and is then threaded into the bracket so that the inner end of said screw engages the said 10 beater-rod 11, and adjustably secures said bracket on said rod.

What I consider a very important portion of my invention is the "balance" of the several moving parts, so that side-strains and 15 lateral friction will be obviated in a great measure. Primarily, this "balance" is brought about by vertically slotting the post 5, so that the treadle-arm 14 passes centrally through the slot 6 of said post; and then 20 mounting the beater-carrying arm 9 in the bifurcation at the upper end of said post, in vertical alinement with the said treadle-arm. Finally, the beater-rod 11, the cymbal-striker bracket 27, and the ball 26, are 25 all centrally mounted with respect to the said post—that is, the weight of all said parts is supported axially by the said post, and there is practically no "side draft" or lateral friction, with the result that the 30 different moving parts never "wabble" or rattle during operation.

Attention is directed now to Fig. 5 of the drawing, where I have shown my improved 35 hoop-clamp applied to the cymbal-holder 31, the cymbal 32 being secured to said holder, by the thumb-screw 33 in the usual manner, while the outer end of said holder is provided with the previously-described hoop- 40 clamp 4, clamping-arms 22, thumb-screws 24, and movable and conformable jaw 25.

The operation is as follows: In case the parts were previously arranged in "knock-down" form for carrying in the pocket, they should of course be assembled again, 45 as shown, by manipulating the various thumb-screws 21, 24, 30 and 12, and by locating the lower end of the treadle connecting-rod 16 in the notch 15 of the treadle-arm 14.

With the parts assembled in the position

in which they are shown in Fig. 1, as well 50 as in Fig. 4, it will be apparent that the operator only need press upon the treadle 2 with his foot to make the necessary contact of the ball 26 with the drum-head, and simultaneously of the cymbal-striker 29 with 55 the cymbal 32 of Fig. 4. All movements are very quick and positive.

In case the operator finds the two springs 17 and 18 too strong, he may readily remove one of said springs. 60

What I claim is:

1. The improved drum and cymbal beater, comprising a single post having an integral one-piece body provided with a slot beneath said body and a fork above said body, a base to which the lower end of said post is attached, a treadle having an arm which projects through the slot in said post, a beater-rod arm 9 mounted in the said fork at the upper end of said post, a beater-rod projecting from said arm, a beater-ball carried by said beater-rod, a lug 20 projecting from said post beneath said beater-rod arm, a spring interposed between said lug and said beater-rod arm, and means for connecting said treadle arm to said beater-rod arm. 75

2. A drum or cymbal beating device adapted to be detachably clamped to a drum-hoop, and comprising a suitable body having 80 clamping-arms which overhang a portion of said body to form a hoop-receiving space, a spring-jaw of flexible material located within said hoop-receiving space in contact with said clamping-arms and adapted to conform itself to the curvature of the drum-hoop, fastening means for permanently but loosely attaching said spring-jaw to said clamping arms, and suitable screws for forcing said spring-jaw into contact with the 85 drum-hoop. 90

In testimony whereof, I have signed my name to this specification, in presence of two subscribing witnesses.

JULIUS A. MEYER.
